UNITED STATES PATENT OFFICE.

WILLIAM H. DAYTON, OF CLEVELAND, OHIO.

DISINFECTING DEVICE.

SPECIFICATION forming part of Letters Patent No. 739,297, dated September 22, 1903.

Application filed May 1, 1903. Serial No. 155,149. (No model.)

To all whom it may concern:

Be it known that I, WILLIAM H. DAYTON, a citizen of the United States, residing at Cleveland, in the county of Cuyahoga and State of Ohio, have invented certain new and useful Improvements in Disinfecting Devices; and I do declare that the following is a full, clear, and exact description of the invention, which will enable others skilled in the art to which it appertains to make and use the same.

My invention relates to a disinfecting device; and the invention consists in the construction and combination of parts, substantially as shown and described, and particularly pointed out in the claims.

In the accompanying drawings, Figure 1 is a perspective view of the device, and Fig. 2 is a vertical sectionalelevation thereof. Fig. 3 is a plan view with the cover or cap open, and Fig. 4 is a modification of the wick-supporting device.

The object of the invention thus shown is to disinfect a room or place where this device is situated through the exposure of the disinfectant upon a surface open to the outer air and over which surface the disinfectant is caused to travel and to evaporate as it goes, as will plainly appear in the further description.

A represents a can or canister, preferably of sheet metal, having its upper half or section *a* liberally perforated to promote circulation of air through the same, and the cap C likewise is preferably perforated more or less for the same purpose, and the cap is designed to be sprung down over the body of the can, so as to lock thereon. A pin *c*, engaging within an opening in spring *c'* upon the body, serves this purpose. This or any other means for holding the cap temporarily in place apart from its own gravity will serve my purpose. Internally I employ a wick D and a suitable wick-support E, also preferably of sheet metal and shown here as a broad strip or piece of sheet metal bent twice at right angles and having its ends resting down upon the bottom of the can and soldered thereon, as seen in Fig. 2, or supported in a removable cup F in the modification Fig. 4. The said wick is designed to work exclusively by capillary attraction and is of a length to

rest one end upon a ledge 2, fixed upon the side of support E and adapted to run under the said support at its opposite end through the opening 3, cut in said side at its bottom, so as to allow the wick to run in over the bottom of the can more or less, as seen in Fig. 2, thereby exposing the wick to the disinfecting liquid in the can, as shown, and enabling the wick to take up the said liquid to the last portion in the can. The ledge 2 serves as a definite stop for the wick, which is always above the level of the disinfecting liquid, and when the wick at that side rests on the said ledge or stop one knows that it is properly placed in position. A pin 4 on the top of the wick-holder serves to secure the wick from sliding on its support, and keepers 5 on opposite sides guide the wick to its place at each side.

As above stated, the wick-holder is shown as soldered or otherwise affixed to the bottom of the can in Fig. 2; but if for any reason it be found desirable to remove said holder and a removable holder be preferred I can supply the style of holder and cup combined shown in Fig. 4. In this case the holder is soldered upon the bottom of cup F, and the said cup itself receives the liquid, which is not supposed to overflow into the can, and the holder and cup can be bodily lifted out of the can when necessary. This style is desirable in case a disinfectant be used which has a tendency to get gummy or to coagulate or harden more or less and which may render it necessary to remove the parts for cleansing.

In operation and having the requisite amount of liquid deposited in the can or cup the disinfectant is drawn up by the wick from its submerged end and carried by capillary action around the circuit and dropped at ledge 2, and in its travel the evaporation goes on and the atmosphere in the room becomes impregnated or charged with the odor thereof, and thus the disinfecting value of the device becomes established. Straps 6 or other means may be employed to fasten the can in place here or there, according to the position it is to occupy and whether it be secured against removal or not.

What I claim is—

1. The can having an open top portion providing for circulation of air, in combination

with a wick-supporting frame therein having a ledge 2 at one side near its lower portion to rest one end of the wick upon, means on said support to prevent the wick from slipping 5 when in place, and keepers on the sides of said support to confine the wick, substantially as described.

2. The can, in combination with a wick-support and a receptacle in which said support is rigidly secured, said support and re- 10

ceptacle being free to be placed within and removed from said can, and a projection on one side of said support serving as a stop for a wick, substantially as described.

Witness my hand to the foregoing specification this 18th day of April, 1903.

WILLIAM H. DAYTON.
